UNITED STATES PATENT OFFICE.

ARTHUR GIESLER, OF DAYTON, OHIO, ASSIGNOR TO THE STILWELL-BIERCE & SMITH-VAILE COMPANY, OF SAME PLACE.

ELECTRIC WATER-WHEEL GOVERNOR.

SPECIFICATION forming part of Letters Patent No. 574,320, dated December 29, 1896.

Application filed April 20, 1896. Serial No. 588,346. (No model.)

To all whom it may concern:

Be it known that I, ARTHUR GIESLER, residing at Dayton, in the county of Montgomery and State of Ohio, have invented certain new and useful Improvements in Electric Water-Wheel Governors, of which the following is a specification.

The object of my invention is to provide a sensitive governor for water-wheels which consists, first, in employing a mechanical governor to control an electric current which operates the reversing mechanism to turn the gate in either direction; second, to provide two electric circuits which are controlled through the governor, which cuts in and out the respective circuits according to the speed, the said circuits being employed to drive the gate-operating mechanism in reverse direction.

A third object of my invention is to provide automatic mechanism for cutting out the circuits soon after the gate mechanism commences to move to prevent racing movement of the governor and also to set the terminals in position for another operation.

The features of my invention are more fully set forth in the description of the accompanying drawings, making a part of this specification, in which—

Figure 1 is a top plan view of my device. Fig. 2 is a front elevation. Fig. 3 is a detailed view of the regulating mechanism operated from the gate-shaft. Fig. 4 is a detailed view of an indicator to show the position of the gates. Fig. 5 is an end elevation of Fig. 1. Fig. 6 is a detailed view of the unshipping-lever mechanism. Fig. 7 is a section on line *v v*, Fig. 1. Fig. 8 is a section on line *w w*, Fig. 1. Fig. 9 is a detailed view of the stop mechanism regulating the friction-clutches. Fig. 10 is a detailed view of one of the transmitting-gears. Fig. 11 is an enlarged sectional view through the governor. Fig. 12 is a section on line *x x*, Fig. 11. Fig. 13 is a section on line *y y*, Fig. 11. Fig. 14 is a detailed view of one of the friction-disks. Fig. 15 is a detailed view of one of the transmitting-gears.

A represents the base of the machine. *B* represents the driving-shaft, driven from the line-shaft by a belt on pulley *B'*. *B*² is a

loose pulley. Power is transmitted by this shaft to the gate-moving shaft *C* through reversing friction mechanism, which consists, preferably, of friction-disks *a b*, which are 55 affixed to a sleeve *c*, splined on the driving-shaft. These friction-disks engage, respectively, with the disks *d e*, according to the direction in which said disks are moved. These disks drive, respectively, worms *f g*, 60 journaled on the shaft *B*, one screw being right and the other left threaded for the purpose of driving the gate mechanism in opposite directions. Motion is transmitted by worm-wheel *G* through shaft 15 and gears *h i* 65 to epicyclic gear on shaft *C*, and motion is transmitted from worm *f* through worm-wheel *G'*, shaft 16, and gears *h' i'* to the opposite side of said epicyclic gears. This train of gears 1 2 3 4 operates in the same manner as shown 70 in Letters Patent No. 540,094, granted the Stilwell-Bierce & Smith-Vaile Company May 28, 1895.

H represents the governor, which is driven from shaft *B* by means of the belt-pulleys 56 75 and bevel-gears 78. Said governor is journaled on the shaft *H'*, which is raised and lowered by the action of the balls to operate the contacts of the circuit-terminals. The sleeve *c* is moved in opposite directions by means of 80 magnets *J K*, which have a common armature *L*, operating an armature-lever *l*, hinged upon a center *l'* and pivoted at its other end to sleeve *L'*, which embraces sleeve *c* for the purpose of shifting the friction-disks. Magnet *J* is energized by means of electric circuit *X*. Magnet *K* is energized by the circuit *Y*. These circuits are respectively connected to a common source of electricity *Z*. The terminals of these circuits are controlled by a 85 common rocking lever *M*, pivoted at *m* to the frame of the governor and operated by the rod *H'* in the following manner: *N* represents a yoke on said lever *M*, embracing the neck *n* of the sleeve *N'*, on which the rod *H'* is adjustably secured, preferably by means of 90 screw-threads. The lever *M* carries terminals *r s* for the respective circuits *X Y*. These terminals are adjustable longitudinally 95 on said lever to regulate the sensitiveness of the governor. When this lever is tilted in one direction, one circuit is closed, and when 100

tilted in the opposite direction the other circuit is closed, and when it is in the normal position both circuits are open. In order to bring the lever back to its normal position 5 when moved in either direction, I provide the following means:

O represents spur-gear on the sleeve N', and O' a rack mounted in the frame of the governor, the teeth of which engage with the 10 teeth of the spur-gear.

o represents a shifting lever operated by the link o'.

P represents the segmental lever, pivoted to arm p, forming part of the sleeve p', which 15 is splined to the box p'.

P' represents a gear driving the segmental lever P and receiving motion through gear Q from gear q on shaft C. I do not wish to limit myself to this means for bringing the 20 lever back to normal position, as other means may be employed.

The operation of the electric governor is very sensitive, and in order to prevent excessive movement in either direction I provide 25 the following mechanism to cut out the circuits soon after contact is made and the friction-disk brought into contact with the driving-gear to move the gates:

R S represent mercury-cups mounted upon 30 carrier-arms T, formed integral with sleeve t, which is swiveled upon a nut U.

u represents a gear-wheel secured to the nut U. The nut U is screw-threaded upon a shaft V, which is provided with a gear v. 35 These gears are driven by the following train of gears from shaft B:

9 represents a shaft provided with a friction-disk 10 and receiving motion through gears 11 12 from beveled gears 13 14 upon 40 shafts 15 16. The gears 13 14 are provided with friction-clutches, so as to engage with the shafts 15 and 16 in their forward movement and to be respectively disengaged from them when the opposite gear is being driven. 45 This shaft 9 always moves in one direction, but is driven intermittently.

17 represents a gear on the shaft B, driving gear 18, which continuously drives a friction-disk 19. The friction-disk 10 drives a friction-wheel 20 on shaft 21, which carries a spur-gear 22, meshing with the gear v, which causes the nut U to descend upon the screw-threaded shaft V.

23 represents a friction-wheel on shaft 24, 50 which drives the gear 25, meshing with gear u on the nut U, which causes the nut to turn upon the threads of the shaft V and elevate the nut and carrier-arms T to their normal position. The gear 25 engages with the shaft 60 24 by means of frictional contact, as shown in detail in Fig. 15, so that when the nut U is raised up to the position desired a suitable stop is provided to terminate the upward movement of the nut U and causes the gear 25 to slip upon the shaft 24.

26 represents a torsional spring acting on the fulcrum of the rod M, and through the

shaft H' upon the governor to prevent undue vibrations of the balls.

27 represents a worm-wheel, and 28 a worm 70 for regulating the tension of the spring 26.

Projecting from the sleeve L' is a stem 29. (Shown in Figs. 8 and 9.)

30 31 represent screw-stops located upon 75 opposite sides of the stem 29 and supported in a yoke 32. The yoke 32 is provided with a collar at its upper end which is screw-threaded to the shaft C, while its opposite or lower end is supported in ways 33. It will be observed that the horizontal diameter of 80 the stem 29 varies and is greatest at its outer end. The screw-threads are on shaft C, upon which the epicyclic gears 3 and 4 are mounted, so that when this train of gears is turned in one direction the yoke-sleeve is 85 moved toward the gears, and when turned in the reverse direction it is moved away from them. This moves the stops 30 31 to or from the outer end of the lever, there being sufficient play between the stops to allow the ordinary gate movement within the limits.

When the screw on the shaft C causes the lever 32 to travel outward, the stops 30 or 31 are brought into engagement with the stem 29 to limit the movement of the armature-lever and the consequent engagement of the friction-disks a b. The object of this is to limit the movement of the gates when necessary, either from lack of water to supply the wheel at full opening or to limit the power 100 of the wheel for any cause. These screw-stops are adjustable to allow any range of opening desired.

In order to enable the operator to operate the gate by hand, the gear 2, which is loosely 105 mounted upon the shaft C, is thrown out of engagement with the gears 3 4 by means of a shifting lever 34, operated by means of a weighted lever 35 and eccentric shaft 37. This is used in starting the wheel. In order 110 to prevent the gate mechanism from being operated in case of accident, and also to close down the gate in case of accidents which require it, I provide the following mechanism:

40 represents a contact-point on the end of 115 the rod M. In case the governor-belt should break or other similar accident the contact would drop onto the contact 41 and establish the circuit through the lines 42 X and also through the line Y. Thus both circuits X 120 and Y are established at the same time, and the effect of the magnet on the armature is neutralized and prevents any gate movement whatever. In case of accidents to the dynamo, such as short-circuiting or similar 125 causes, so that the circuits X Y become inoperative or anything throwing the load off the wheel, the balls would raise and depress the rod M until contact was made between 40 and 43. This would make contact in circuit 130 44, which is the circuit of a separate exciter, storage battery, or similar source of current 45, which would operate circuit X and close the gates. In order to cushion the movement

of the rod M, I provide the ordinary dash-pot 46.

By the construction herein shown and described the control of the gate is operated directly through a governor which directly controls electric circuits which operate the reversing mechanism of the transmitting train of gears. I also provide automatic safety controlling devices to either shut down the gate or prevent gate movement, according to the nature of any emergency which prevents the proper action of the governor.

Mode of operation: When it is desired to start the wheel by hand shifting, lever 35 is turned down, disengaging the gear 2, so that the shaft C can be turned by hand and the gates opened. The shifting mechanism is then thrown back. The electric current is turned on the circuits X Y, which are normally open. When the balls expand, the circuit X is closed, and the gate-opening is contracted by the operation of the devices already described. When the governor-balls are contracted, the circuit Y is established and the gates are opened wider. At each of these movements the carrier T is quickly drawn down, breaking the circuit to prevent excessive movement, and slowly brought back into contact position for a second operation, the rod M being returned to its normal position during this operation. By this means I obtain a very sensitive governor and am enabled to control the speed of the water-wheel under varying loads in a highly satisfactory manner. I do not wish to limit myself to the specific means described for producing this result except where the same are made specific elements of the claims.

I claim—

40 1. In a machine for controlling the movement of water-wheel gates, the combination with a governor positively driven by the water-wheel, of two electric circuits the terminals of which are controlled by said governor, mechanism operated by the circuits for actuating gate-operating mechanism in both directions, and means operated by the governor for quickly breaking the circuits to prevent excessive movement of the gate and slowly bring 45 back the parts into position for the next operation, substantially as described.

2. In a device for controlling water-wheel gates, employing a governor operating two circuits, two terminals, two opposing terminals, and mechanism for automatically moving said opposing terminals away from the primary terminals and returning the same to their normal position, which mechanism is brought into operation by the closing of either 50 of said circuits, substantially as specified.

3. In combination with an electric governor operating two circuit-terminals, two electric circuits adapted to be opened and closed thereby, mechanism operated by said circuits 55 controlling a shifting lever for bringing into operation alternate trains of driving - gears

driven by a main shaft, mechanism for automatically returning the governor-termsinals to their normal position, operated through said gate-shaft, substantially as specified. 70

4. In combination with a governor positively driven, two electric circuits, terminals for said circuits operated alternately by mechanism controlled by the variations of the governor's speed, two secondary terminals supported upon a carrier, two sets of driving mechanism one of which is in continuous operation, and the other mechanism is intermittently brought into operation by the closing of either circuit, and mechanism operated thereby for returning said secondary terminals to their normal position, substantially as specified. 75

5. In combination with a positively-driven governor journaled upon a vertically-moving shaft, the movement of which is controlled by the variable governor speed, electric-circuit terminals connected to and operated by said shaft, adjusting mechanism connected to one end of said shaft and operated automatically by a power-gear and lever mechanism to adjust said primary terminals independent of the governor-ball adjustment, whereby said terminals are automatically brought into their normal position, substantially as specified. 85

6. The combination of a positively-driven governor journaled upon a vertically-moving shaft which is raised or lowered by the variable governor speed, circuit-terminals mounted upon a lever operated by said governor-shaft, an independent terminal connected to said lever and adapted to engage at its extreme movement in one direction with the terminal of a branch circuit 42, substantially as specified. 90

7. In combination with a positively-driven governor journaled upon a vertically-moving shaft, a primary electric-circuit terminal connected to and operated by said shaft, a secondary opposing terminal supported upon a carrier, power mechanism connected to and operated by the mechanism set in motion by the circuit established by the primary terminal, whereby said terminals are moved to and from contact, substantially as specified. 105

8. The combination of a positively-driven governor journaled upon a vertically-moving shaft which is raised or lowered by the variable governor speed, circuit-terminals mounted upon a lever operated by said governor-shaft, an independent terminal connected to said lever and adapted to engage at its extreme movement in one direction with the terminal of a branch circuit 44, whereby the circuit is 110 maintained and the train of gears for closing the gate is kept in motion, substantially as specified. 125

9. In a machine for controlling the movement of water-wheel gates, the combination with a governor which controls an electric circuit, of a lever-shipping mechanism oper- 130

ated by said circuit, and adjustable stops for limiting the movement of the shipping lever, substantially as specified.

10. In a machine for controlling the movement of water-wheel gates, the combination with a governor which controls an electric circuit, of a lever-shipping mechanism operated by said circuit and a traveling graduated guide moving between said stops and connected with the shipping lever whereby the

movements of the electrically-controlled shipping lever are determined by the adjustment of said stops, substantially as specified.

In testimony whereof I have hereunto set my hand.

ARTHUR GIESLER.
